shown and described.

DESCRIPTION

FIG. 1 is a perspective view of a golf club head, as viewed
from below, rear and one side, according to one embodiment.

FIG. 2 is a front elevation view of a golf club head of FIG.
1.

FIG. 3 is a rear elevation view of the golf club head of FIG.
1.

FIG. 4 is a side elevation view of a toe side of the golf club
head of FIG. 1.

FIG. 5 is a side elevation view of a heel side of the golf club
head of FIG. 1.

FIG. 6 is a top plan view of the golf club head of FIG. 1; and,
FIG. 7 is a bottom plan view of the golf club head of FIG.
1.

The broken lines in the drawings are for purpose of illus-
trating environmental structure as well as portions of the
design that form no part of the present claimed design. The
dash-dot broken lines represent the boundary and form no
part of the claimed design.

The drawings are lined for the color black within the oval
dot-dash lines.
